United States Patent Office.

WILLIAM PARKIN, OF TAUNTON, MASSACHUSETTS, ASSIGNOR TO
REED & BARTON, OF SAME PLACE.

Design No. 3,705, dated October 5, 1869.

DESIGN FOR A TEA-SERVICE.

The Schedule referred to in these Letters Patent and making part of the same.

To all persons to whom these presents may come:

Be it known that I, WILLIAM PARKIN, of the city of Taunton, of the county of Bristol, and State of Massachusetts, have invented or produced a new ornamental Design for a Tea-Service; and do hereby declare the same to be fully represented in the accompanying drawing, and to be thus described, the said drawing exhibiting a front elevation of a teapot.

The body A of the pot is cylindrical in its horizontal section.

It rests on four feet, b, each of which, on its front, is provided with a sphinx in *alto reliefo*. Each leg extends up from the bottom, and projects from the outer surface of the body, and is formed parallel, and ornamented in manner as shown, there being, at the

middle of the extension of the leg, a lion's head in relief, supporting, from its mouth, a pendant of flowers.

The handle B, formed as shown, has such another lion's head and pendant at the upper part of each side of it.

The cover C is surmounted by a knob, D, having a series of lions' heads in relief projecting from it.

The spout or nose E is panelled on each face, and otherwise formed as represented.

I claim the ornamental design for the body and feet, the handle, the spout, and the cover and its knob, as represented.

Witnesses: WILLIAM PARKIN.
